UNITED STATES PATENT OFFICE

WILLIAM E. COLE, OF MONTGOMERY, ALABAMA.

BRICK-DRIER.

SPECIFICATION forming part of Letters Patent No. 378,236, dated February 21, 1888.

Application filed August 16, 1887. Serial No. 247,081. (No model.)

To all whom it may concern:

Be it known that I, WILLIAM E. COLE, a citizen of the United States, residing at Montgomery, in the county of Montgomery and State of Alabama, have invented certain new and useful Improvements in Brick-Driers, of which the following is a specification, reference being had therein to the accompanying drawings.

10 My invention relates to devices for evaporating the moisture of bricks and other material; and the objects of my improvement are to produce an inexpensive box-floor, in connection with shielding boards, for drying bricks by steam, as specifically set forth in the claim. 15 I accomplish these objects by the construction illustrated in the accompanying drawings, in which—

Figure 1 is a perspective view of a box-floor constructed in accordance with my invention. Fig. 2 is a top view of the same, partly broken away and the side boards removed to show the internal parting-blocks to support the top sheet of the floor and the heavy 25 weight that may be placed thereon. Fig. 3 is a transverse vertical section of the same box-floor placed under a shed.

In said drawings, A represents the foundation or ground upon which rests the box-floor 30 B, that may be five to eight feet wide and a hundred and fifty feet long, more or less. This floor is in the form of a shallow rectangular box about an inch deep, having a sheet-metal top, b, and a bottom, b², either of sheet metal 35 or of matched and well-fitting boards to form a smooth surface, upon which steam or water can travel with very little friction. If both the top and bottom are of sheet metal, their edges may be suitably bent and riveted together; but if the bottom is made of wood, said 40 top and bottom are nailed to wood parting strips b³, placed adjacent to their edges, that at the same time keep said top and bottom at a proper distance apart. Suitable packing is 45 placed between said edges and the strips b³, to render the box-floor steam-tight when its edges are secured together. Within this box-floor are also placed a series of parting-blocks, b⁴, to support the top b at a substantially uniform 50 distance from the bottom, and also to support the weight of bricks or other material to be

dried upon said floor; but said blocks are at such distances apart as not to interfere with the circulation of steam in any direction within the box-floor. A pipe, d, is inserted in one 55 end of this floor, to admit steam therein either from the exhaust-pipe of an engine or live steam direct from the boiler in the night-time when the engine is at rest, or from a boiler used specially for that purpose. 60

The box-floor is slightly inclined downward toward one end, preferably the end opposite that in which the steam is admitted, to direct to that end the water resulting from the condensation of steam, and said water is carried 65 off through a pipe, d², that may be provided with a trap and a cock, whereby its escape can be partly prevented and also regulated.

To concentrate the caloric ascending from the top plate, b, of the box-floor when steam is 70 circulating therein and prevent winds from carrying it away too rapidly, there is placed a series of boards, C, alongside of the box-floor. Said boards stand substantially vertically on their edges, and are preferably hinged 75 at c to the box-floor. Short posts or standards C² are placed at the ends of each board, to which said boards can be secured by hooks c² or any other suitable means. The box-floor is preferably placed under sheds E, as usually 80 found in brick-yards, to keep rain from falling upon the drying bricks.

By the above inexpensive means bricks can be made and dried during all the seasons of the year and in wet as well as in dry weather. 85

Having now fully described my invention, I claim—

The combination of a box-floor consisting of a metal top plate, b, and a bottom, b², united at their edges, and a series of parting-blocks 90 between said top plate and bottom, with a steam-leading pipe at one end and an escape-pipe at the other, and boards C, secured alongside of said box-floor, substantially as and for the purpose described. 95

In testimony whereof I affix my signature in presence of two witnesses.

WILLIAM E. COLE.
